VARIABLE-INDUCTANCE COIL.

Application filed November 22, 1924. Serial No. 751,494.

This invention relates to a variable inductance device, and more particularly to such a device adapted for use in radio frequency circuits.

5 In such inductances it is now common to provide a stationary coil and a movable coil, connected in series, and so arranged that the axes of the two coils may be varied relatively to each other, whereby their magnetic interlinkage may at will be made to vary between the full cumulative and the full differential condition. The cumulative position corresponds to the maximum inductance setting, while the opposite differential position corresponds to the minimum inductance setting. All this is now well understood, and is set forth herein to define the type of device to which our invention relates.

20 It is one of the objects of our invention to provide in general an improved form of such variable inductances.

It is still another object of our invention to provide a plurality of variable inductances which may be operated by the aid of a single movable member, such as a shaft, and set relatively closely together without danger of the elements interfering, due to their stray fields or the like.

30 In variable inductance coils of this general character, it is highly desirable that the movement of the movable coil relatively to the stationary coil be proportional to the effect of such movement on the circuit in which the coil is placed. For example, in a radio receiving system, when tuning to receive signals from a station, the tuning is usually produced by varying the resonance or the wave length at which the receiving circuit is in tune. It is highly desirable that substantially equal increments of wave length variation be secured for equal increments of variation of the coil position.

40 In prior devices, the movable and stationary coils were so arranged and were so constructed that this characteristic could not readily be obtained. One contributing reason for this is that upon a variation in the relative positions of the two coils, there is a corresponding variation in the distributed capacity between the coil layers. It is possible to secure a more uniform calibration by insuring that the distributed capacity stays constant, or substantially so, for any 50 setting of the two coils. It is thus another object of our invention to ensure that the

distributed capacity of the variable inductance stays substantially constant within the range of operation of the instrument.

Our invention possesses other advantageous features, some of which with the foregoing, will be set forth at length in the following description, where we shall outline in full that form of the invention which we have chosen for illustration in the drawings accompanying and forming part of the present specification. Although we have shown in the drawings but one form of our invention, we do not desire to be limited thereto, since the invention as defined in the claims 70 may be embodied in other forms also.

Referring to the drawings:

Figure 1 is a side view showing an installation utilizing a pair of variable inductances built in accordance with our invention, one of the inductances being in section;

Fig. 2 is a perspective view of one of the coil elements utilized in our invention; and

Figs. 3 and 4 are diagrammatic views, illustrating how the positions of the coils may be varied to vary the effective inductance of the entire device.

The stationary coil element of our device comprises one or more coil sections 11 which are arranged in a circle, as shown diagrammatically in Figs. 3 and 4. The magnetic axis of these coils is, indicated by the arrow 12 in Figs. 3 and 4, and is seen to be radial with respect to the circle formed by the two coils 11. The actual construction of the coils may be best appreciated by an inspection of Fig. 2, in which we have shown the coils 11 as made up of a single layer of turns. It is seen that the long sides of the coils 11 are arcuate in shape, so as to fit within the hollow tubular support 13 as shown in Fig. 1. This support is stationary and is held as by the aid of one or more brackets 14 to a stationary panel 10. The coils 11 may be held to the inner surface of the tubular support 13 by the aid of appropriate fastening devices or by glue, collodion, or the like.

The tubular support 13 in this instance has an end wall 15, which supports a central hub 16, serving as a bearing support for the main operating shaft 17. In Fig. 1, we illustrate a pair of stationary supports 13, through which the shaft 17 extends; but it is to be understood that any number of such supports, each corresponding, may be aligned as required for the particular installation.

The movable coil element is formed of two coils 18 located in this instance within the circle formed by the coils 11, and rotatable with respect thereto. These coils also 5 extend angularly for a sufficient distance to form substantially a complete circle, each extending about 180° and have magnetic axes which are coplanar with the axis 12 of the stationary coils 11. The axis for the coils 18 10 is indicated by the arrow 19 in Fig. 3, and the arrow 20 in Fig. 4. The magnetic axes of all the coils are not only coplanar, but fall substantially along radii of the tubular support 13.

15 The coils 18 are given a revolutionary movement by the rotation of shaft 17, which has an axis coaxial with that of the tubular support 13. For this purpose there is mounted on the shaft 17 a rotatable support 20 21, which has a tubular portion 22. On the outer cylindrical surface of this portion 22 are fastened the coils 18. The support 21 is held on the shaft 17 by the aid of any appropriate means, such as the set screw 24 25 passing through a hub 23 formed integrally with the support 21.

The coils 11 and 18 are all connected in series in any circuit that is to be tuned. By 30 rotating shaft 17, it is possible to vary the relative position of the axes of the two sets of coils 11 and 18. In this way, the coils may be changed from full cumulative position to full differential position by a rotation through 180° degrees. Thus in Fig. 4 35 the full differential position is indicated. The arrow 12 indicates the axis and amount of the magnetic field set up by the coils 11; while the arrow 20 shows the equal and opposite effect of the movable coils 18. These 40 two values substantially neutralize each other, and the device is then in the minimum inductance position. By rotating the shaft 17 in a clockwise direction, the full differential position is departed from and 45 the total inductance of the device gradually increases. Thus for the intermediate position illustrated in Fig. 3, the axes of the two sets of coils are illustrated by the arrows 12 and 19, which are at right angles to each 50 other. In this position the vector sum of these two arrows represents the effective inductance of the device. By continuing the rotation of shaft 17, the coils will fall in a position which is similar to that illustrated 55 in Fig. 4, except that the two arrows 12 and 20 would be drawn in the same direction and not in the opposite direction. This is the full cumulative position, and corresponds to the maximum inductance obtainable by the 60 use of our device.

Several features of the construction of the device may now be emphasized more particularly. One feature which is of great importance, resides in the fact that the coils 65 11 have a field which is limited to a substan-

tially narrow band extending around the axis of shaft 17. It is for this reason that it is possible to mount two variable inductance devices near to each other, as illustrated in Fig. 1, with the assurance that they 70 will not have stray magnetic effects upon each other to any material extent. This effect is obtained by using arcuate coils, in which the axial length is comparatively small, and also due to the fact that the outer 75 coils 11 for all positions of the device encompass the inner coils 18. Thus there is no departure from the radial direction of the axes of all of the coils, with respect to the axis of shaft 17. The net result is that 80 the resultant magnetic field of any one set of coils, is confined to a narrow band around the axis of shaft 17.

It is further to be noted that coils 11 and 18 have an angular extension sufficient to 85 form substantially a complete circle or ring. Due to this feature, the distributed capacity which exists between the two layers of coils, remains substantially constant independent 90 of the relative positions of the coils. This distributed capacity is produced by the juxtaposition of one set of conductors making 95 up the coils 11, with respect to the other set adjacent thereto making up the coils 18. The calibration of the instrument is found 100 to be more uniform, since it is found that equal angular movement of shaft 17 produces equal increment in the wave length to which the circuit is to be tuned.

Since we are able to utilize two or more such devices on a common shaft 17 without interference, it is quite feasible to tune a plurality of circuits simultaneously by the operation of a single shaft such as 17. Such 105 a feature is of considerable importance where a plurality of tuned radio circuits are used, as for example in tuned radio frequency amplifier stages in radio receiving systems. Of course, other applications may also be found for our invention.

It is also evident that the particular shape of the coils 11 and 18 may be materially departed from, while yet maintaining some of the advantages of our invention.

We claim:

1. In combination, a pair of relatively movable coils, each of said coils being of loop form, two opposite sides of the loop corresponding to the periphery of a surface of revolution, these sides extending over a 120 large angle of said surface, and displaced from each other along the axis of the surface so that the coils extend only a short axial distance as compared with the angular extent of the coil, the coils of the pair being placed on parallel surfaces of revolution so as to affect each other, and means for supporting the coils so that the coil axes form radii of the said surfaces of revolution.

2. In combination, a plurality of station-

125

ary coils, said coils being of loop form, two opposite sides of each coil corresponding substantially to the periphery of a surface of revolution, these sides being displaced from each other along the axis of said surface, the coils being angularly displaced in such manner that the combined angular extent of these sides extends substantially completely around the said periphery, the other opposite sides of the loops being short whereby they occupy a narrow space only along the axis of the surface of revolution, a plurality of cooperating movable coils similarly arranged to the stationary coils and also having sides the combined angular extent of which extends substantially around a similar periphery parallel to the other periphery, the stationary and movable coils having axes radial to said surfaces, and means for moving the movable coils so as to vary the relative angular positions of the axes of the coils, whereby the extent of adjacent surfaces of the stationary and movable coils remains substantially unaltered during the said movement.

3. In combination, a plurality of pairs of relatively movable coils, each of said coils being of loop form, two opposite sides of the loop corresponding to the periphery of a surface of revolution, these sides extending over a large angle of said surface, and displaced from each other along the axis of the surface so that the coils extend only a short axial distance as compared with the angular extent of the coil, the coils of each pair being maintained on parallel surfaces of revolution, so as to affect each other, and the plurality of pairs being displaced from each other in a direction along the common axis of the said surfaces, and means for simultaneously varying the relative angular positions of the coils in each pair.

4. In combination, a pair of stationary coils, said coils being of loop form, two opposite sides of each coil corresponding substantially to the periphery of a surface of revolution, these sides being displaced from each other along the axis of said surface, and each extending substantially 180° along the periphery, and said pair of coils forming in combination a substantially complete ring along said periphery, the other opposite sides of the loops being short whereby they occupy a narrow space only along the axis of the

surface of revolution, a pair of cooperating movable coils similarly arranged to the stationary coils and each also having sides extending substantially 180° along a periphery similar and parallel to the other periphery, and both movable coils forming a substantially complete ring, the stationary and movable coils having axes radial to said peripheries, and means for moving the movable coils so as to vary the relative angular positions of the axes of the coils, whereby the extent of the adjacent surfaces of the stationary and movable coils remains unaltered during said movement.

5. In combination, a plurality of pairs of stationary coils, said coils being of loop form, two opposite sides of each coil corresponding substantially to the periphery of a surface of revolution, these sides being displaced from each other along the axis of said surface, the coils of each pair being of equal angular extent and angularly displaced in such manner that the combined angular extent of these sides extends substantially completely around the said periphery, the other opposite sides of the loops being short whereby they occupy a comparatively narrow space only along the axis of said surface of revolution, a plurality of pairs of movable coils similarly arranged to the stationary coils and each pair also having sides the combined angular extent of which extends substantially completely around a similar periphery parallel to the other periphery, these stationary pairs of coils and movable pairs of coils being arranged to cooperate with each other so that a pair of stationary coils cooperates with a pair of movable coils to form a unit, the plurality of units thus formed being displaced from each other along the common axis of the said surfaces, means for moving the movable coils simultaneously so as to vary the relative angular positions of the axes of the coils in each unit, whereby the extent of adjacent surfaces remains substantially unaltered during said movement, and whereby the electrical field of the coils in each unit remains in a comparatively short space along the axis of revolution.

In testimony whereof, we have hereunto set our hands.
